HERMETIC REFRIGERATION COMPRESSOR

Jens Touborg, Tecumseh, Mich., assignor to
Tresco, Inc., a corporation of Michigan

Application November 28, 1949, Serial No. 129,738

7 Claims. (Cl. 230—58)

1

This invention relates to compressors of the type adapted to the compression of refrigerant vapor, and it is particularly concerned with a compressor in which is incorporated a lubricant pump to supply oil to the working parts thereof. The present invention includes subject matter which is also described in my prior and copending application, Serial No. 51,348, filed September 27, 1948, and to that extent this application may be deemed a continuation in part.

One of the problems presented in connection with small or fractional horsepower compressors, to be used in conventional refrigerating systems, is the elimination of noise. Another problem is to assure adequate supplies of lubricant to the working parts, such as the motor shaft. It has heretofore been proposed to include a small auxiliary pump in the compressor assembly to deliver oil to the working parts, but it has been found, under many conditions of operation, that a pump having adequate capacity also generated a relatively loud noise, and thus detracted from one of the desired attributes of the compressor. Another problem encountered in the provision of a lubricant pump is that many proposals require a substantial number of additional parts, complicated porting and conduit arrangements and the like, and thus unduly increase the cost.

According to the present invention, a lubricant pump of high capacity, and which has been found to be substantially noiseless in operation, is built into the compressor assembly, and is so devised as to require substantially no additional parts, and a minimum of machining operations. In a preferred embodiment of the invention, the pumping effect is obtained by inclining a reciprocating piston-in-cylinder compressor with respect to the axis of the drive shaft, and utilizing the resulting relative linear motion between the crank pin and piston yoke to force oil into a duct drilled in the drive shaft. Additionally, the crank pin is also inclined to the axis of the drive shaft, to impart an arcuate oscillatory motion to the piston about its longitudinal axis, as well as a linear reciprocating motion. The compounded motion of the piston provides a wiping action within the cylinder, which laps or polishes out score marks that might otherwise be formed by adventitious dirt particles. Such motion moreover maintains the piston in motion in at least one direction at all times, and thus further eliminates or reduces a noise factor which is an incident to, or inherent in, reciprocating pistons whose linear motion is truly or approximately harmonic.

2

The principles of the invention, and the advantages to be derived therefrom, will be made apparent from the following description of a typical embodiment, illustrated in the accompanying drawings, wherein:

Fig. 1 is a vertical section through a hermetic compressor incorporating the invention;

Fig. 2 is a bottom plan;

Figs. 3 to 6 inclusive are enlarged fragmentary horizontal sections through the cylinder and piston assembly of the compressor, showing the relative positions of the parts at ninety degree intervals during a complete revolution of the drive shaft;

15 Figs. 7 and 8 are enlarged fragmentary vertical sections through the cylinder and piston assembly, showing the positions corresponding to those shown in Figs. 3 and 6, respectively;

Fig. 9 is an exploded view, partly in section and 20 partly in elevation, of the drive shaft, crosshead, and piston and yoke of the compressor;

Fig. 10 is an additionally enlarged bottom plan of the crosshead; and,

Fig. 11 is a top plan of the piston and yoke 25 assembly.

Referring primarily to Figs. 1 and 2, the compressor (in common with that disclosed in my above identified prior application) comprises a two-part casing or shell including flanged sections 21 and 22, which are relatively shallow with respect to their diameters, and which are welded together after assembly to provide a hermetically sealed compressor. Within the casing are an electric motor 23, main casting 24, and a refrigerant pump or compressor 25, all of which are connected together and are resiliently mounted in spaced relation to the casing walls. The casting 24 is generally annular in form, and it is provided at diametrically opposed points with outstanding lugs 26, each of which is transversely bored to receive mounting means, as will presently be described. The casting 24 is centrally formed with an upstanding bearing boss 27, which is axially bored to receive a vertically disposed main drive shaft 28, whose ends project both above and below the boss.

The upper end of the shaft 28 receives a bored and counterbored quill 31 provided with a sleeve 32 whose lower end is supported on the upper end of the boss 27 through the medium of a thrust washer 33. The sleeve is suitably connected to the upper end of the shaft 28, as, for example, by means of a press fit. A motor rotor 34 is also press fitted into the quill 31. 50 The motor stator 35 is mounted on a shoulder 36

formed on the periphery of the casting 24, and it is secured in position by any suitable means, such as bolts, not shown. The motor lead wires 37 extend to terminals 38 which pass through the wall of the casing section 22, and into a relay box 39, welded to the casing, wherein the indicated electrical connections may be made.

The casting 24 and the parts connected thereto are internally mounted in the casing by a resilient suspension cooperating with the casting lugs 26. The casing sections are each provided with spaced pad portions 41, 42, located substantially radially equidistant from the longitudinal axis of the cylindrical dimension of the casing, and in an axial plane parallel thereto. Opposed pads may therefore be brought into alignment when the casing sections are superimposed. As described in detail in my aforesaid copending application, each pad is provided with an abutment or socket 43 which is welded thereto, to receive the ends of transversely extending spring supporting and retaining rods 44, which pass through tapped apertures 45 in the lugs 26. Each rod is surrounded by a coiled spring 46 which also passes through the aperture 45.

The springs 46 are both helical and cylindrical, and they are screwed into the apertures 45 to project on each side thereof the proper distance to center or locate the compressor assembly within the casing. While the springs contact the lugs, they do not contact the rods 44 except at the ends thereof, where they are bent into a generally hairpin convolution to grip the rod on opposite sides, and around a small key 47 formed on either end thereof. These keys prevent rotation of the springs and rods relative to each other after the assembly has been made and adjusted. The casing section 22 is also provided with depending brackets 48, disposed above the lugs 26, to which are connected one end of tension springs 49, whose opposite ends engage openings formed in ears 51 of the lugs 26. The springs 49 absorb some of the weight of the assembly, and, in conjunction with the springs 46, permit the resilient mounting of the parts in such fashion that forced vibrations, and resulting noise, is minimized.

The refrigerant pump unit 25 comprises a cylinder block 55 having a cylinder 56 bored therein, the head end of which is covered by a valve plate 57 and cylinder head 58. Inasmuch as the details of the valves form no part of the present invention, and suitable structure is more fully described in my prior application, a further description of these parts appears unnecessary. The cylinder block 55 is secured to the under side of the casting 24 by bolts 59. A piston 61 is reciprocably mounted in the cylinder 56 by means of an offset or crank portion 62 formed on the lower end of the main shaft 28, and below a crank arm 63 which carries a counterweight 64. The crank 62 rotatably fits into a diametrical bore 65 of a cylindrical crosshead 66, which is carried for transverse reciprocatory movement in a yoke 67, integrally connected at right angles to the crank end of the piston 61. As thus far described, the driving connection will be recognized as of the Scotch yoke type, but it involves certain important variations from the conventional yoke drive, as will presently be explained.

In operation, rotation of the motor rotor 34 causes reciprocation of the piston 61, to draw returning refrigerant vapors into the cylinder 56 on the suction stroke, and to discharge compressed refrigerant on the compression stroke.

The returning vapors enter through a suction line 71 at the top of the casing, flow around the motor to absorb some of its heat, and enter the cylinder head 58 through a suction tube 72 which extends upwardly in the casing and above the oil level therein. The discharged vapors pass through a discharge line 73 which is advantageously coiled in the oil bath at the bottom of the casing, and which terminates in an outlet line 74 passing through the casing wall. The compressor is adapted to be included in the usual compressor - condenser - expander refrigeration system, which needs no description here.

Considering further the cylinder and piston and drive assembly, it will be seen, in Fig. 1 and some of the enlarged views, that the cylinder block 55 and the cylinder bore 56, are inclined at a slight angle to the horizontal plane. Similarly, while the motor and bearing portions of the main shaft 28 are disposed in a vertical plane, the crank portion 62 is inclined to the vertical plane. The piston 61 is, of course, also necessarily inclined to the horizontal plane, and it follows that it is not at right angles to the vertical. These inclinations depart from customary practice, and lead to the improvements with which the present invention is primarily concerned. It may here be noted that while this angularity may be varied within reasonably wide limits, the drawings have here been laid out for deviations from the horizontal and vertical reference lines or planes for a fairly small angle, between two and three degrees. This is sufficient for a compressor subject to the intended service of the illustrated unit.

As will be readily understood by those conversant with the Scotch yoke linkage, rotation of the drive shaft 28 about its own axis causes an orbital movement of the crank pin 62, which, in the usual or conventional case, describes or sweeps out a right cylinder whose axis coincides with the axis of the drive shaft. The crank pin 62 rotatably fits in the bore 65 of the crosshead 66, and the crosshead is guided in the bore of the transverse yoke 67. During one revolution of the drive shaft, the crosshead will therefore move lengthwise of the yoke with a linear reciprocatory motion, and the crosshead, yoke, and piston will also have a linear reciprocatory motion with respect to the longitudinal axis of the cylinder 56. The successive positions assumed by these parts are shown in Figs. 3 to 6, wherein Fig. 3 represents the end of the suction stroke and the beginning of the compression stroke. Counterclockwise rotation as viewed in these figures, will be assumed throughout the balance of the description. The piston 61 is then beginning to move to the left, and the crosshead 66 is moving in an upward direction.

In the ensuing ninety degrees of rotation, the displacement of the crank pin 62 has moved the crosshead 66 upwardly to the limit of its travel in this direction, and has also moved the piston 61 about half way in its stroke into the cylinder 56. This is shown in Fig. 4. In Fig. 5, the end of the compression stroke has been reached, and the displacement of the crankpin has caused the crosshead to recede from the upper end of its travel, and to be again in a central position. Fig. 6 illustrates the positions reached in the next ninety degrees of rotation, when the piston 61 is partially withdrawn, and the crosshead has reached the lower limit of its transverse motion. The motion of the crank pin transversely of the yoke 67 is made possible by a slot 76 formed in

the upper portion of the yoke, and the length of the pin 62 is such as to terminate adjacent the innermost chord taken through the arcs of intersection of the bore 65 and the periphery of the crosshead 66.

As noted, the piston 61 and crank pin 62 are inclined to the normal axes, and therefore the arcuate motion of the crank pin is not such as to describe a cylinder, but rather a cone or frustum of a cone. That is to say, the inclination of the crank pin 62 causes its lower extremity to sweep through a circle of larger diameter than that traced by its upper end. As the crank pin 62 is fitted uniformly in the cylindrical bore 65 of the crosshead 66, it will be apparent that the crosshead will have a rocking or pendulum like motion about the vertical axis as it moves from one end of the yoke to the other. Similarly, the inclination and motion of the crank pin will cause the yoke 67, and the connected piston 61, to have a rocking motion about the vertical axis. In Figs. 3 to 6, wherein the vertical axis is normal to the plane of the paper, the rocking motion of the piston 61 is the same as an arcuate oscillatory motion of the piston about the axis of the cylinder 56, and it is herein illustrated by black dots on the piston surface, which show the displacement on either side of the center line. If these successive dot positions were connected, they would outline a relatively long oval or ellipse.

The effect of the combined linear and arcuate movements of the crosshead in the yoke, and the piston in the cylinder, is to change the alignment between longitudinal lines of contact between the pairs of arcuate surfaces, thus producing a wiping or lapping action which otherwise would not be obtained. This motion is beneficial, as it serves to effect a better distribution of the oil films between the surfaces, and it increases the resistance to the introduction of small dirt particles which would cause scoring.

Another important feature of the compound motions of linear reciprocation and arcuate oscillation is that the piston is always in motion in at least one direction, either axially or transverse to the bore of the cylinder 56. As will appear from the motion diagrams, Figs. 3 to 6, the piston is at mid-stroke when the crosshead 66 is at the end of its stroke, and vice versa. Stated otherwise, the linear and arcuate motions are out of phase, and, in this particular case, by approximately 180°. Inasmuch as the end of the displacement or stroke of a body having harmonic motion is accompanied by a reversal of direction of motion, the body, at the instant of reversal, has a zero velocity, while maximum velocity occurs as it passes through its central point of reference. Thus, when the piston 61 reaches the end of its linear movement or stroke, its arcuate velocity is at its maximum, and the piston is therefore always in motion. It has heretofore been observed that the reversal of stroke of a conventional piston-in-cylinder compressor has been accompanied by a slight hiss or noise, which was considered to be inherent and irreducible. It has now been discovered that by imparting the described compound and continuous motion to the piston, this source of noise is eliminated.

As heretofore noted, the inclination of the piston with respect to the horizontal axis is also utilized to provide a simple and effective lubricant pump, in which no additional moving parts are required. Considering particularly Fig. 9, the drive shaft 28 is formed on its periphery above the crank arm 63 with a spiral groove 81,

which, in association with the bearing surface of the sleeve 27, provides a passageway through which oil may be delivered to the bearing, and also to the top of the rotor quill 31. Oil discharged from the top of the shaft 28 may drain down through the rotor clearance gap into ducts 82, 83, formed in the casting 24 (see also Fig. 1), for delivery to the exposed portion of the piston 61. The excess oil falls by gravity to the oil bath contained in the bottom or crankcase portion of the casing.

The lower and crank pin portions of the shaft 28 are longitudinally drilled to provide a duct 84 which communicates with the groove 81 through a radial port 85. The crank pin 62 is formed with a radial slot 86 which intersects the duct 84, and the lower end of the duct, below the slot 86, is stopped off with a plug 87 after the shaft has been machined. The crosshead 66 is formed with a transverse or vertical groove 88, which may be machined in the wall of the bore 65 from one end thereof a sufficient distance to overlap the radial slot 86 when the parts are assembled. The crosshead 66 is also formed with an angularly inclined, transversely disposed or tangential slot 89, disposed on the external surface and extending upwardly from the bottom of the bore 65, and in spaced relation to the groove 88. An oil groove 90 is also formed circumferentially of the crosshead 66, to supply lubricant to the bearing surface against the yoke 67.

The yoke 67 is formed with a port 91, positioned above the lower trace of the yoke, and which is in open communication with a flattened suction or riser tube 92, welded to the bottom of the yoke, the lower end of which is adapted to dip into the oil bath. Both the tangential slot 89 and the oil groove 90 are adapted to pass over the port 91 when the compressor is operated.

It will now be apparent that, as the piston 61 reciprocates, its yoke end moves downwardly with respect to the crank pin 62 on the suction stroke, and upwardly on the compression stroke, due to the inclination of the piston with respect to the horizontal. Inasmuch as the lower end of the crankpin 62 is adjacent the junction of the bore 65 with the wall of the crosshead 66, there is a small well or reservoir 93 constituting, in effect, a cylinder or pump chamber in which the crank pin reciprocates as a piston. Referring again to Figs. 3 to 8, it will be seen that, as the piston 61 reaches the end of its compression stroke (Fig. 5) the angular slot 89 in the crosshead 66 is about to register with the port 91 in the yoke 67, and thus place the slot 89 in fluid communication with the oil bath. As the shaft 28 continues to rotate, this communication becomes fully established, as shown in Fig. 6, and the reservoir 93 also is in fluid communication with the oil bath, since the slot 89 extends downwardly thereto, as is clearly shown in Fig. 8. The crosshead is moving downwardly over the crank pin 62, to increase the volume of the reservoir 93, and the suction effect causes oil to flow into the reservoir as long as the fluid passageway is open.

During this same time, the trailing edge of the radial slot 86 in the crank pin 62 has moved past the longitudinal duct 88 in the crosshead, thus closing off this passage, and preventing flow of oil therethrough. As the crosshead 66 moves back to its central position the port 91 progressively closes, and is cut off by the body of the crosshead as the end of the suction stroke is reached, as shown in Fig. 3. As the compression stroke begins, the leading edge of the radial slot

86 opens the duct 88, and the pressure created by the upward motion of the crosshead 66 with respect to the crank pin 62 forces the oil into the radial slot 86, and thence into the longitudinal duct 84. The lubricant is then distributed as heretofore described.

It has heretofore been stated that the actual inclination of the piston to the horizontal, and the crank pin to the vertical, may be a small angle of only two or three degrees. Preferably, both piston and crank pin are inclined, and they are inclined equally with respect to their reference axes. However, this condition need not be fulfilled within the broader principles of the invention. For example, further consideration of the Figures will show that, with equal angularities, the axes of the crank pin and the piston are at right angles to each other when the crank pin has revolved 180° from the position shown in Fig. 1. Thus, the angularities become additive on the suction stroke, and the small angularity of each provides a displacement for the oil pump which would not otherwise be obtained if the crank pin axis were also vertical. In this case, the angularity of the piston would be increased to obtain the same displacement. When a larger inclination of the piston is desired, and noise is not so much of a factor, the crank pin axis may be vertical. It will, of course, be understood that references to vertical and horizontal planes and axes are made for convenience of description, and not to limit the invention to compressors mounted in one specific manner.

It will thus be seen that a positive displacement oil pump has been formed from the basic elements of the driving connection itself, that is, the drive shaft, crosshead, and yoke, and in which no additional moving parts are required. In my prior application, a system of porting through the driving elements is also disclosed, but with added parts to provide a pump cylinder and piston. As with the lubricant pump of my prior invention, the present pump is so organized as to have its suction and pressure strokes coincide substantially with the suction and compression strokes of the refrigerant compressor.

The present pump is quite noiseless in operation, and, while the displacements are numerically small, they are sufficient to supply adequate quantities of oil to the bearings and other working parts. In fact, the present pump delivers enough oil that a portion of it may be sprayed against the casing walls to aid in cooling, being thrown off centrifugally from the exposed upper end of the groove 81, while the remaining portion drips through the rotor gap to lubricate the piston. The provision of the depending suction or riser tube 92 on the yoke 67 makes it unnecessary to submerge the yoke and cylinder block in the lubricant.

While the invention has been described with respect to a single embodiment thereof, it will be apparent to those skilled in the art that numerous modifications and alterations may be made without departure from its principles. It is therefore intended that the invention should be accorded a scope commensurate with that expressed in the following claims.

I claim:

1. A compressor having a crankcase portion 70 and a cylinder block formed with a cylinder bore, a piston reciprocably mounted in the cylinder bore and provided with a transversely disposed yoke at the crankcase end thereof, a crosshead slidably mounted in the yoke and formed with

8
a diametrical bore, a drive shaft having a crank pin portion rotatably mounted in the crosshead bore, a bearing for rotatably mounting the drive shaft for rotation about its own axis, said cylinder bore and piston being angularly inclined with respect to the axis of the drive shaft, said yoke being positioned with its axis at right angles to the axis of the piston, whereby upon rotation of the drive shaft the crank pin and crosshead bore have linear movement relative to each other, an oil duct extending longitudinally of the crank pin to the drive shaft bearing, an oil bath in the crank case portion, and ports formed in the crosshead adapted to be alternately opened and closed in timed relation to the linear movement of the crosshead to alternately subject oil in the oil duct to pressure and to replenish oil discharged from the duct from the oil bath.

2. A compressor having a reciprocable piston mounted in a fixed cylinder, said compressor having a crank case portion adapted to contain a bath of oil, a drive shaft formed with a crank pin inclined to the axis of the drive shaft, a bearing for supporting the drive shaft for rotation about its own axis, a crosshead having a diametrical bore in which the crank pin is rotatably mounted, a yoke surrounding the crosshead and connected to the piston with the axes of the piston and yoke at right angles to each other, said yoke having an imperforate wall beneath the bore of the crank pin, said piston having its axis inclined to the axis of the drive shaft, whereby upon rotation of the drive shaft the piston will reciprocate linearly in the cylinder and will also oscillate about its own axis and said crosshead will reciprocate linearly in the yoke, oscillate about its own axis, and reciprocate linearly of the crank pin to change the volume of the space between the end of the crank pin and said imperforate wall of the yoke, porting means formed in the crosshead and adapted, when said space is increasing in volume, to place said space in communication with the oil bath, an oil duct extending longitudinally of the crank pin to said bearing, and additional porting means between the pin and duct to place said duct in communication with said space when it is decreasing in volume.

3. In a compressor having a supporting casting and a drive shaft rotatably mounted in a bearing in the casting for rotation about its own axis, a cylinder block formed with a cylinder bore connected to the casting, a reciprocable piston in the cylinder bore, said piston and bore having a common axis inclined to the axis of the drive shaft, a yoke connected to the crank case end of the piston, the axis of the yoke being disposed at right angles to the axis of the piston and transversely of the shaft axis, a cross head formed with a diametrical bore slidably mounted in the yoke, a crank pin on the drive shaft rotatably mounted in the crosshead bore, the end of the crank pin terminating short of the end of the bore to form a reservoir between the end of said crank pin, the wall of the bore, and the wall of the yoke, a lubricant duct having one end adapted to be placed in communication with the reservoir extending longitudinally of the crank pin to the drive shaft bearing, valve means in the crank pin and crosshead for establishing said communication during one phase of rotation and for interrupting said communication during a successive phase, additional valve means in the crosshead and yoke for interrupting and establishing communication between said reservoir

and the exterior of the yoke alternately to the operation of said first named valve means, and means exterior of the yoke to supply oil to said reservoir when said reservoir is in communication with the exterior of the yoke through said additional valve means.

4. A combined refrigerant compressor and oil pump comprising a cylinder and a piston reciprocably mounted therein, a drive shaft and a bearing for the drive shaft, and a Scotch yoke connection between the shaft and piston, said yoke comprising a yoke cylinder disposed at right angles to the piston and connected thereto and a cylindrical crosshead slidably mounted in the yoke, a bore in the crosshead, a crank pin on the drive shaft rotatably mounted in the bore, said piston being inclined to the axis of the shaft, a casing for the piston and shaft adapted to contain a bath of oil, ports formed in the yoke and crosshead adapted to be aligned during one phase of movement of the shaft and piston and upon alignment to admit oil from the casing to the crosshead bore, a duct extending longitudinally of the crank pin to the bearing, and other ports formed in the crosshead and crank pin adapted during a successive phase of movement to transfer oil from the bore to said duct and bearing.

5. In a refrigerant compressor having a reciprocable piston fitted in a fixed cylinder and a drive shaft rotatably mounted in a fixed bearing, a Scotch yoke connection between the shaft and piston comprising a cylindrical yoke connected to the crank end of the piston at right angles to the axis thereof and a cylindrical crosshead reciprocably mounted in the yoke, said crosshead being formed with a diametrical bore and said drive shaft being formed with a crank pin rotatably mounted in said bore, the axis of the piston being inclined to the axis of the drive shaft, said yoke being formed with an oil admission port disposed within the outermost trace of the crosshead bore, said crosshead being formed with a tangential slot communicating with the bore and adapted upon reciprocation of the crosshead to periodically register with and be displaced from said port, an oil duct formed in the crank pin and extending to the bearing, a radial slot formed in the crank pin communicating with the duct, and a groove in the bore adapted to register with the radial slot during that phase of motion of the crank pin and crosshead when the tangential slot is displaced from said port.

6. In a refrigerant compressor having a reciprocable piston fitted in a fixed cylinder and a drive shaft rotatably mounted in a fixed bearing, a Scotch yoke connection between the piston and shaft including a cylindrical yoke connected to the piston at right angles to the axis thereof, a cylindrical crosshead slidably mounted in the yoke and formed with a diametrical bore, a crank pin on the drive shaft rotatably mounted in said

bore, said piston being inclined to the axis of the drive shaft and said crank pin also being inclined to the axis of the drive shaft at an angle substantially equal to the inclination of the piston to said shaft, an oil reservoir formed between the end of the crank pin, crosshead bore, and yoke surface, a crank case for the compressor containing a bath of oil, and porting means formed in the crank pin, crosshead, and yoke adapted upon successive phases of rotative movement of the shaft to admit oil from the crank case to the reservoir and to transfer oil from the reservoir to the bearing.

7. A hermetic refrigerant compressor comprising a casing having a supporting casting therein, a motor mounted on the casting, a bearing formed in the casting and a drive shaft rotatably mounted in the bearing, said drive shaft projecting beyond the bearing at each end thereof and being formed with an oil groove, a cylinder block mounted on the casting and formed with a cylinder bore, a piston reciprocably mounted in the cylinder bore, a cylindrical yoke connected to the crank end of the piston at right angles thereto, said piston and cylinder bore being inclined to the axis of the drive shaft, a crosshead slidably mounted in the yoke and formed with a diametrical bore, a crank pin formed on one end of the drive shaft and extending beyond the bearing and rotatably mounted in the crosshead bore, a bath of oil in the casing, an oil duct formed in the crank pin and communicating with the oil groove of the drive shaft, ports formed in the yoke and crosshead adapted to register during one phase of movement of the drive shaft to admit oil from the oil bath to the region between the end of the crank pin, crosshead bore, and yoke, other ports formed in the crank pin and crosshead adapted to place said region in communication with said oil duct during a successive phase of movement, said oil groove extending the full length of the drive shaft and to the opposite end thereof beyond said bearing, whereby oil forced into said groove may be transferred from said opposite end of the shaft to the motor and the casing walls to absorb heat therefrom, and a drain duct in said casting adjacent the crank end of the piston and cylinder block to direct at least a portion of the oil to the piston.
